BENJAMIN H. HIBLER, OF MCKEESPORT, PENNSYLVANIA, ASSIGNOR TO HIMSELF AND PITTSBURG AND MCKEESPORT CAR COMPANY.

Letters Patent No. 67,651, dated August 13, 1867.

IMPROVED TUYERE FOR BLAST-FURNACE.

The Schedule referred to in these Letters Patent and making part of the same.

TO ALL WHOM IT MAY CONCERN:

Be it known that I, BENJAMIN H. HIBLER, of McKeesport, in the county of Allegheny, and State of Pennsylvania, have invented a new and useful Improvement in Tuyeres; and I do hereby declare the following to be a full, clear, and exact description thereof, reference being had to the accompanying drawings, making a part of this specification, in which—

Figure 1 is a side elevation of my improved tuyere.

Figure 2 is a vertical section of a furnace cupola showing the position of the tuyere; and

Figure 3 is a longitudinal vertical section of the tuyere.

Like letters of reference indicate similar parts in each.

The nature of my improvement consists in the construction and arrangement in the cupola or fire-space of a furnace, of an improved tuyere, whereby the blast is discharged into the cupola at or near its centre, or at some point inside the inner face of the cupola wall or lining, and in providing such tuyere with proper apertures for the dissemination of the blast throughout the cupola or fire-space.

To enable others skilled in the art to make and use my invention, I will proceed to describe its construction and mode of operation.

In smelting-furnaces of the ordinary construction, the blast pipe, either with or without some form of tuyere, discharges directly into the cupola, and its inner end is usually flush with the inner face of the cupola wall or lining. Two or more such blasts are commonly introduced at different points in the cupola. Such mode of introducing the blast is objectionable for the reasons that the air of the blast not being distributed through the cupola uniformly, does not produce a uniform heat throughout the cupola, nor act to the same degree on every part of the molten metal, and consequently the metal produced is not of a perfectly homogeneous character. The blast is, moreover, liable to become clogged by an accumulation of slag directly over or around the mouth of the blast pipe. To obviate these and other difficulties, I have devised a tuyere through which to discharge into the cupola the air from the blast pipe, and which consists of a pipe, *a*, connected by its open end, *b*, with the blast pipe, and projecting forward into the cupola *m* to or toward its centre. The other end *b'* I open directly into the fire-space of the cupola, or, as shown in the drawings, I turn it upward in an elbow shape, and provide an aperture, *c*, of any desirable size or shape on its under side, opening downwards. The top or upper end of the elbowed part *b'* I usually make close, and give it a cap shape, with overhanging projections *d*, so that the apertures *e*, just below, shall be protected from slag, molten metal, &c. These apertures *e* are of any desirable number, size, or arrangement, and in connection with the aperture *c* they allow of the free dissemination of the air of the blast through all parts of the cupola, securing a more uniform heat, the greater rapidity in the smelting process, and a better and more homogeneous quality of metal. Also by the aperture *c* I bring a current of air in contact with the melted iron in the bottom of the cupola, waiting to be drawn off, and thereby continue the decarbonizing process, which the smelting to some extent necessarily involves. I thus not only prevent the melted iron from becoming "dead," but render it more "lively," and capable of being cast into smaller moulds, and into the small interstices and apertures of large moulds, so as to form smaller or more angularly-shaped articles of manufacture. The apertures *e*, under the projecting edges of the cap *d*, provide for the dissemination of the air of the blast uniformly throughout that part of the cupola where the smelting process is being carried on, so as to secure more perfectly the advantages of a blast. To protect the tuyere described from the effects of the excessive heat to which it is exposed, I usually cover it with a mortar of fire-clay, as shown at *n*, fig. 2, or such other material of a similar character as is a poor conductor of heat. That such mortar may adhere firmly to the tuyere, I corrugate or roughen the outer surface of the latter, or make on it projections, &c.

The tuyere shown in the drawings is of the form which I find best adapted to the object in view, but I also find that a simple pipe leading from the end of the blast pipe as ordinarily constructed, or a prolongation of the blast pipe into the cupola, to or toward its centre, and with an open head, or with one or more apertures in a closed head, or in a pipe, or both, is a material improvement on the present style of blasts, and I include such

Improvement in my invention. The tuyere described is made of cast iron, or such other well-known material as is adapted to such uses.

What I claim as my invention, and desire to secure by Letters Patent, is—

1. A tuyere consisting of a pipe or the prolongation of the blast pipe of a smelting-furnace, when such tuyere extends into the cupola beyond the inner face of its wall or lining, and to or toward the centre of the cupola, substantially in the manner and for the purposes above set forth.

2. A tuyere having an elbowed head, with a cap, *d*, projecting outward, so as to cover the apertures *e e*, constructed and operating substantially as and for the purposes described.

3. One or more apertures, *e*, in the lower side or face of the tuyere or tuyere pipe of the cupola of a smelting-furnace, so as to discharge a portion of the air of the blast against the molten metal in the bottom of the cupola, substantially in the manner and for the purposes above set forth.

In testimony whereof I, the said BENJAMIN H. HIBLER, have hereunto set my hand.
